UNITED STATES PATENT OFFICE

GIOVANNI PEDRAZZO, OF BIELLA, ITALY

CONTACT FINGER FOR ELECTRIC MACHINES AND APPARATUS

Application filed July 21, 1930, Serial No. 469,511, and in Italy July 30, 1929.

My invention relates to a new and improved form of contact fingers for electric machines, and similar apparatus.

More particularly, my invention is designed to ensure a proper operation of the contact fingers, in addition to reducing the production costs.

Among other advantages, my invention is characterized in its facility of installing the contact finger, in combination with its holder, in an electric apparatus, etc., an operation which can be performed by any fitter. With my construction there is no need of adjusting the finger of contact surface relative to the movable part of the said electric apparatus.

In addition, my invention possesses the advantage that the pressure of the spring which biases the contact finger, in combination with the devices which will be described hereinafter, has a tension only sufficient to ensure the proper contact of the finger or contact surface against a movable part of the electric apparatus; since as a consequence the spring has no other load, it can be comparatively small, and therefore extremely sensitive. The sensitive pressure of the spring itself therefore permits the finger, in combination with the said devices, to contact over its full contact surface against the said movable part of the electric apparatus, and to be maintained in the position of good contact required by the said movable part. It results from the foregoing that the full contact surface of the finger will always follow the operating surface of the movable part of an electric apparatus, with which the contact finger is designed to cooperate.

Still further, my invention permits the adequate regulation of the position of the contact finger relative to a movable part of the electric apparatus, by any fitter. The finger automatically adapts itself throughout its contact surface, against the said movable part and ensures perfect contact even in the instance that the finger or contact surface is not perfectly parallel to the said movable part; viz: the contact finger adapts itself in parallel relation against the said movable part, and maintains such position.

The operation of the movable part of the

electric apparatus provided with contact fingers according to my invention is very sensitive; that is, the workman operating the said movable part is required, as a result of my construction, to overcome only a minimum of operating force.

It is readily understood that the good contact ensured by my invention permits a uniformity in operation of the machine, as well as considerably reduced operating cost as compared with the prior art devices.

My invention is disclosed, merely by way of example, as consisting of three distinct features, which will be better explained by reference to the figures of the drawings, in which:

Fig. 1 shows schematically, in operating position, an example of contact fingers, in side elevation, partly in section, fully illustrating the three elements forming the object of my invention, which elements are shown in section together with the cooperating parts;

Fig. 2 shows a plan view of the apparatus of Fig. 1;

Fig. 3 shows schematically in section, on the line A—A of Fig. 1, an example of one of the elements according to my invention;

Fig. 4 shows schematically in section, on the line B—B of Fig. 1, an example of another element (rear side, opposite to the contact), according to my invention;

Fig. 5 shows schematically in section, on the line C—C, of Fig. 1, an example of still another element (central), according to my invention; and

Figs. 6 and 7 are vertical sections through still another constructional embodiment of my invention; while

Figs. 8 and 9 disclose, in vertical section, yet another modification thereof.

Referring to Fig. 1 the holder 1 carries the contact finger 10, while the clip 2 serves, by means of the bolts 3, to fix the holder 1 on the insulating bar 4. Flexible cables are shown at 5, having a terminal plug soldered at each end, serving to transmit the current from the holder 1 to the contact finger 10, the said cables being formed by flexible wires and being placed in such manner as to avoid undesirable mechanical impediments to the

operating movement of the contact finger; a bolt 6 serves to fix the cables 5 on one side and also to fix the strand conductor (not shown) transmitting the current to the holder 1. The contact 7 by means of the bolt 8, is fixed to the finger 10, which is shown in operating position against the contact surface of the movable part 9.

A ball or spheroidal journal 11 is fixed to 10 the finger 10 by means such as a nut 12, which in combination with the corresponding groove 13 of the holder 1, forms one of the constructional forms of the left-most or front device of Fig. 1 according to my invention, 15 and is better shown in Fig. 3, in its operating position against a contact (of a movable part not shown) which is not parallel to the contact 7 of the finger 10. The said front device prevents the contact finger 10, 7 from deviating 20 from its operating direction and also supports the contact finger itself when in its rest position in the holder 1 by means of the extremity of the spheroid 11 which rests in the bottom of the groove 13 of the said 25 holder 1, thus supporting the finger adjacent its front part. Hence it follows that, in the said front device, formed by the said ball journal (or spheroid) and by the said corresponding groove, the spheroid 11 can roll 30 in a sliding fashion from right to left and vice versa, within the walls of the groove 13 of the holder 1 during which the finger 10, 7 (in its operating movement) does not encounter any undesirable mechanical 35 impediments.

A ball or spheroidal journal 14 is shown as fixed to the finger 10 by means such as a nut 15, which nut, in combination with the corresponding cavity 16 of the holder 1, forms 40 one of the constructional forms of the right-most or rear device (the side opposite to the contact) according to my invention, and is better shown in Fig. 4, in operating position against a contact of a movable part not 45 shown, which contact is not parallel to the contact 7 of the finger 10. The said device 14, 15, 16 serves to support the rear extremity of the finger 10, 7 in the holder 1 by means of the spheroid 14 resting in the cavity 16 of the holder 1. It follows, therefore, that in 50 the said rear device formed by the said ball or spheroidal journal and by the said corresponding cavity, the spheroid 14, which can roll slidingly in the corresponding cavity 16 of the holder 1, permits the contact finger 10, 7 in its operating movement, to accomplish 55 freely a ball and socket joint movement without encountering any undesirable mechanical impediments, the center of the spheroid 14 forming the center of the joint.

The nut 15, which fixes the spheroidal journal 14 in the finger 10 also serves to fix the terminal plug of the cables 5, transmitting the current from the holder 1 to the finger 10.

60 A journal 17 is fixed at one end to the hold-

er 1, which journal serves to carry the spring 20 which biases the finger 10, and also carries the special nut 21 which serves to regulate the pressure of the spring 20 and to release the same. Still further, the said journal 17 carries, in combination between the spring 20 and the finger 10, the convex body 18 and the concave body 19, which together form one constructional form of the central device located between the front and the rear device, 75 according to my invention.

The said bodies 18 and 19 are better shown in Fig. 5, in an operating position where the finger 10 is not parallel to the holder 1, due to the fact that the contact 7 shown in Fig. 1, is located against a movable part (not shown) which is not parallel to the said holder 1. The said convex body 18, applied against the finger 10, always follows the finger throughout its operating movement. To permit the finger 10 a certain freedom of movement or play with respect to the journal 17, a hole of larger diameter than that of the journal 17 is provided in the finger 10 and in the body 18. The concave body 19 moves about the journal 17, in combination with the spring 20, by means of the reciprocating stroke of the finger 10, similar to a movable, hollow cylinder moving on a fixed piston. It follows therefore that the convex surface of the body 18 can slide in the ball and socket joint movement in the concave surface of the body 19, so that the contact finger 10, 7, during its operating movements, does not encounter any undesirable mechanical impediments, and 100 automatically in combination with the pressure or friction exerted by the spring, remains in contact with the movable part 9, even if the latter is not perfectly parallel to the holder 1. In the drawings, Fig. 1 and Fig. 5, the 105 convex body 18 is shown as existing separately. It is evident however that if desired, it can also be constructed solidly with the contact finger 10 (Figs. 6 and 7). It must be noted that the said central device, according 110 to my invention, can be placed in a number of different ways. In addition to the use of a tensioned spring instead of a compression one, the user can also construct the journal 17 in such manner as to move freely in a bearing 24 fixed to the holder 1, (Figs. 6—9) and can fix the concave body 19 to one of its extremities and the nut 21 at the other extremity (Figs. 8—9), in order to obtain the same 115 result, with the difference that the spring has thus become tensioned instead of under compression. In such case the journal 17, will, in addition to the body 19 and the body 18, be interposed between the spring and the contact finger.

In Fig. 5 there is further shown, somewhat schematically, one of the constructional forms of a device according to one part of my invention, according to which one can construct many types of contact fingers, provided 120

only that between the device which either presses or pulls the contact finger, a body with concave surface and a body with convex surface are interposed, which bodies can 5 slide one in the other, in a ball and socket joint movement.

It is readily understood that once the broad aspects of my invention have been disclosed, numerous modifications and adaptations thereof, falling within the scope of the invention, will readily occur to those skilled in the art.

Accordingly, it is intended that the invention be limited only by the scope of the appended claims.

I claim:

1. In combination, a contact finger for electric machines and apparatuses having a free front end and a supported rear end, a 20 cooperating contact surface with which the front end or free extremity of the contact finger is adapted to engage, a pivot on which the rear or supported end of the contact finger is mounted, the said pivot comprising 25 an approximately ball-shaped member on the finger, a support having a cavity adapted to receive the said ball-shaped member, a spring device, washers having concave and convex surfaces mounted about the central part of 30 the finger, and interposed between the finger and the said spring device, said ball-shaped member and said concave-convex washer providing for universal movement of the contact finger and for the automatic adjustment 35 of its free end transversely of the cooperating contact surface.

2. In combination, a contact finger for electric machines and apparatuses having a free front end and a supported rear end, a 40 cooperating contact surface with which the front end or free extremity of the contact finger is adapted to engage, a pivot on which the rear or supported end of the contact finger is mounted, the said pivot comprising 45 an approximately ball-shaped member on the finger, a support having a cavity adapted to receive the said ball-shaped member, a spring device, a second approximately ball-shaped member mounted on the finger, the 50 said support having a corresponding groove within which the second ball-shaped mem-

ber is received, for further guiding the finger in relation to the support, washers having concave and convex surfaces mounted about the central part of the finger and interposed between the finger and the said spring device, said ball-shaped member and said concave-convex washers providing for universal movement of the contact finger and for the automatic adjustment of its free end transversely of the cooperating contact surface. 70

3. In combination, a contact finger for electrical apparatus having a free front end and a supported rear end, a cooperating contact surface with which the front end or free extremity of the contact finger is adapted to engage, an aperture extending through said contact finger, a spring pressed shaft extending through said aperture and seating in the supporting member for said contact finger, washers having cooperating concave and convex surfaces mounted on said contact finger about said shaft, the spring on said shaft tending to hold said washers in engagement, the said washers providing for universal movement with the contact finger, and for automatic adjustment of its free end transversely of the cooperating contact surface. 75

4. In combination, a contact finger for electrical apparatus having a free front end and a supported rear end, a cooperating contact surface with which the front end or free extremity of the contact finger is adapted to engage, an aperture extending through said contact finger, a spring pressed shaft extending through said aperture and seating in the supporting member for said contact finger, cooperating concave and convex surfaces on said contact finger about said shaft and movable relatively to each other as a ball and socket joint, the spring of said shaft tending to maintain said surfaces in engagement, the said surfaces providing for universal movement of the contact finger and for automatic adjustment of its free end transversely of the cooperating contact surface. 85 90 95 100 105 110 115

In testimony whereof I have signed my name to this specification.

GIOVANNI PEDRAZZO.
